UNITED STATES PATENT OFFICE.

HENRY JAMES HICKEY AND WARNER E. McMULLAN, OF FORT DODGE, IOWA.

DESIGN FOR A GUIDE-POST.

55,859.

Specification for Design.

Patented July 20, 1920.

Application filed June 19, 1919. Serial No. 305,442. Term of patent 3½ years.

To all whom it may concern:

Be it known that we, HENRY J. HICKEY and WARNER E. McMULLAN, citizens of the United States of America, and residents of Fort Dodge, Webster county, Iowa, have invented a new, original, and ornamental Design for a Guide-Post, of which the following is a specification.

Our invention consists in the new, original and ornamental design for a guide-post as

herein claimed and illustrated by the accompanying drawing, in which—

Figure 1 is a plan and Fig. 2 is an elevation of a guide-post embodying our design.

We claim as our invention—

The ornamental design for a guide-post as shown.

HENRY JAMES HICKEY.
WARNER E. McMULLAN.
